United States Patent Office

Des. 181,610
Patented Dec. 3, 1957

181,610

WRIST WATCH BRACELET

John F. Sand, Convent Station, N. J., assignor to The Gemex Corporation, New York, N. Y., a corporation of New Jersey

Application June 21, 1956, Serial No. 41,998

Term of patent 14 years

(Cl. D45—4)

Fig. 1.

Fig. 2.

Fig. 3.

Fig. 1 is a plan view of the wrist watch bracelet embodying my new design;

Fig. 2 is an enlarged plan view showing a portion of my said wrist watch bracelet; and

Fig. 3 is a view in side elevation, partly in section, of my said wrist watch bracelet taken on line 3—3 of Fig. 2.

I claim:

The ornamental design for a wrist watch bracelet, as shown.
